UNITED STATES PATENT OFFICE

147,369

DESIGN FOR A COOLER

Raymond Loewy, New York, N. Y., assignor to
The Coca-Cola Company, Wilmington, Del., a corporation of Delaware

Application December 21, 1945, Serial No. 124,915

Term of patent 14 years

(Cl. D67—4)

To all whom it may concern:

Be it known that I, Raymond Loewy, a citizen of the United States and resident of New York, New York County, New York, have invented a new, original, and ornamental Design for a Cooler, of which the following is a specification, reference being had to the accompanying drawings, forming part thereof.

Fig. 1 is a view in perspective showing the front, top and one end of a refrigerator cabinet embodying my new design; and

Fig. 2 is also a perspective view but showing the rear, top and other end thereof.

I claim:

The ornamental design for a cooler, as shown.
RAYMOND LOEWY.
